CONVERTIBLE WASHING MACHINE

George K. Parsons, Detroit, Mich., assignor to
Unitor Corporation, Detroit, Mich., a corpora-
tion of Michigan

Application February 23, 1932, Serial No. 594,679

11 Claims. (Cl. 68—15)

This invention relates to labor saving devices, and more particularly to a machine suitable for use in private households, compact, generally somewhat resembling a washing machine, adapted to be folded out of the way when not in use, yet incorporating therein means for efficiently mechanically performing a wide variety of household tasks, in fact the majority of those household tasks capable of being performed mechanically.

The invention also includes among its objects provision of such a machine to which may be attached accessories for performing other personal services such as hair-drying, providing mechanical exercise and the like.

The invention constitutes an improvement upon that disclosed in my copending application Serial Number 530,117, filed on the fourteenth day of April, 1931.

20 A further object of my present invention is the provision, in such a machine incorporating a main tub, of a combined lid and auxiliary tub construction adapted when closed to provide a tightly sealed cover, and when opened to provide an auxiliary tub of relatively large capacity. Novel means for slidably mounting and locking the combined lid and auxiliary tub are further contemplated as objects of my invention.

25 A still further object resides in the provision of improved means for detachably affixing the various accessories to the machine.

Improved means for mounting and for controlling the swinging and folding of the machine are also objects of this invention.

30 Among the objects should also be noted the embodiment in the device of an improved clothes washer and an improved dishwashing construction, improved accessories affixable to the machine, and an improved transmission and transmission-controlling mechanism.

35 Other objects and advantages will be apparent from the following description wherein reference is made to the accompanying drawings illustrating preferred embodiments of my invention and wherein similar reference numerals designate similar parts throughout the several views.

In the drawings:

Figure 1 is a side elevational view of my improved household machine, showing the same in upright position and ready for use, standing in front of a sink, which is fragmentarily shown, and beneath which the entire machine is foldable when not in use;

50 Figure 2 is a side elevational view taken at

right angles to Figure 1, looking in the direction indicated by the arrow 2 of Figure 1;

5 Figure 3 is a front elevational view showing the machine folded over and ready for swinging beneath the sink;

Figure 4 is a top plan view of the machine in the same position, also showing a sink, and showing in dotted lines the position the machine occupies when swung therebeneath;

10 Figure 5 is a fragmentary front elevational view of the top portion of the machine, showing the combined lid and auxiliary tub at the upward limit of its movement preparatory to its being swung to opened position;

15 Figure 6 is a similar elevational view showing the combined lid and tub member fully opened;

20 Figure 7 is a fragmentary detail elevational view, partly broken away, looking substantially in the direction indicated by the arrow 7 of Figure 5;

25 Figure 8 is a vertical sectional view through the supporting standard, the tub and tub supports and a portion of the sub-base being broken away, taken substantially on the line 8—8 of Figure 1 and looking in the direction of the arrows;

30 Figure 9 is a fragmentary detail sectional view taken substantially on the line 9—9 of Figure 2 and looking in the direction of the arrows, the electrical wiring being omitted in the interests of clarity;

35 Figure 10 is a fragmentary vertical sectional view taken substantially on the line 10—10 of Figure 2 and looking in the direction of the arrows;

40 Figure 11 is a detail fragmentary sectional view taken substantially on the line 11—11 of Figure 10 and looking in the direction of the arrows;

45 Figure 12 is a side elevational view of the machine swung to another possible position enabling convenient scouring of the tubs;

50 Figure 13 is a vertical sectional view taken substantially on the line 13—13 of Figure 6 and looking in the direction of the arrows, additionally showing a whipping or beating attachment mounted upon the cross bar;

55 Figure 14 is a top plan view of a hair-drying attachment also attachable to the device by mounting the same upon the cross bar, the cross bar being fragmentarily shown;

Figure 15 is a vertical sectional view of the hair-drying attachment taken substantially on the line 15—15 of Figure 14;

55 Figure 16 is a side elevational view of the hair-

drying attachment looking in the direction indicated by the arrow designated 16 in Figure 15, and

5 Figure 17 is a top plan view of the transmission and motor driving unit.

Referring now to the drawings: Reference character 15 indicates a tub, here shown as stamped of sheet metal, substantially octagonal in cross section and supported upon legs 16, 17, 10 18 and 19, to which its sides may be directly secured, by spot welding, riveting or in any other suitable manner. The tub may taper somewhat toward its base, being in my preferred form, as shown, wider at the top than the bottom. The 15 legs are supported by a sub-base 20, upon which, and beneath the tub, are mounted the driving motor 21 and transmission 22. The transmission-controlling or gear shifting means, which is carried by and within the housing 23, is supported by the leg 16, to which the housing is secured, as shown in Figures 1 and 2. An electrical outlet and switch box 24 are also carried by the leg 16, being supported thereby upon its other side in similar and symmetrical fashion. 20 25 The housings 23—24 may be formed integrally if desired. The switch, the toggle lever of which is marked 25, may be arranged to turn on and off the current supply to the motor 21 and plug socket 26 simultaneously.

30 The sub-base 20, and so the entire machine, which is supported thereby, is swingable about a horizontal axis provided by the shaft 27, which is supported by the vertical standard 28. The entire machine is also swingable about a vertical axis provided by the shaft 29 carried by and rigidly upstanding from the main base 30. The sub-base 20 is fixed to the shaft 27, as by means of the set screw 31 (Figure 8), and the shaft therefore rotates as the machine is swung about 35 40 the horizontal axis. A counterbalance spring 32 is provided to neutralize the weight of the machine, and permit easy swinging movement thereof in this manner. The spring is housed within the box 33 formed in the top of the 45 vertical standard 28, the inner end of the spring being fastened to the shaft 27, as shown in Figure 9, while its outer end is adjustably fixed by the hooked bolt 34, which extends through the side of the housing, and is longitudinally movable by means of the adjusting and securing nut 35. The horizontally extending portion 38 of the standard, in which the shaft 27 is journaled, is best stiffened by a web as 36. The base 30 and the shafts 29 and 27 may be hollow, as shown 50 in Figure 8, and the electrical wiring to the motor may extend therethrough, as there shown. The flexible B—X cable in which the wire is housed is designated 37, and one or more fuses, as 39, may be housed in the box 33.

55 60 To control the swinging movements of the machine suitable detent mechanisms may be provided. As shown in Figure 8, swinging of the machine about the vertical axis is controlled by a detent pin 40, vertically slidable in a slide- 65 way 41, the bottom of which opens adjacent the top of the boss 42 of the base 30, which supports the shaft 29. The upper surface of the boss 42 is formed with one or more notches, as 43, in which the detent is adapted to engage and 70 into which it is urged by the spring 40'. The pin may be drawn clear of the notch or notches by means of the operating lever 44, the lower extremity of which is forked, one arm extending on each side of the box portion 33 of the stand- 75 ard and fastened to each end of the shaft 45

by pins as 46. A lever 47 is secured to the shaft within the housing, and is connected to the pin 40 by a link 48, which may be of wire. In order to release the pin from the notches 43 and permit swinging of the machine about the vertical axis it is necessary to move the lever 44 to the right (as viewed in Figures 2 and 8)—farther however than is possible when the machine is upright, as when this is the case the leg 19 blocks sufficient movement of the lever to 10 release the pin 40. This feature prevents swinging the machine when standing upright and thus guards against its striking the sink when the machine is installed as shown with respect to a sink (49).

15 In order to similarly lock and release the machine with respect to swinging movement about a horizontal axis, I provide an additional detent pin, as 50, horizontally slidable in a slideway 51 formed in the top portion of the standard 20 28 and opening adjacent the leg 19 of the machine, which is notched or cupped as at 52 in such manner that the pin 50, by engaging in the notch, is adapted to lock the machine in an upright position. The compression spring 25 53 for the detent pin is trapped behind the pin in the inwardly opening hollow boss 54 formed upon the cover plate 55 of the box 33. The inwardly opening bore 56 not only houses the spring 53 but provides an additional support- 30 35 40 45 50 55 60 65 70 75 80 85 90 95 100 105 110 115 120 125 130 135 140 145 150 155 160 165 170 175 position and securable to the other side of the web when the machine is reversed.

The tub-supporting legs 15, 16, 17, 18 are preferably of rigid and relative strong construction and extend up the sides of the tub to points adjacent the top thereof. The tub itself supports no weight except the weight of its contents. The combined lid or cover and supplementary tub member 63 is also formed of sheet metal, of such size and shape as to freely vertically slide within the tub 15. Its supporting framework comprises a saddle 64 having spaced side rails 65 integrally extending down the hinged side of the member 63. Rods 66 extend vertically between the rails, being rigidly supported by the same integral casting, which includes the upper portion 64 of the framework, the side rails 65 and the transversely extending lower portion 67. The positioning of the slide rods 66 is best shown in Figures 7 and 10, and as also there shown, the rods are slideable in a hinged block 68 pivotally secured to the leg 17 adjacent the top of the tub 15, as by the hinge pin 69. It will be seen that by lifting the combined cover and auxiliary tub member 63 to the upward limit of its travel, at which point it is stopped by engagement of the bottom cross member 67 with the hinge plate 68, the lower edge of the member 63 will be elevated sufficiently so that its sides will no longer interfere with swinging the lid to opened position (note Figures 5 and 6). Lifting handles for the cover-auxiliary tub assembly may be provided in the form of rods 70-71 extending between the spaced side members of the saddle portion 64, the handle-retaining portions of the side rails being preferably somewhat elevated and reinforced, as shown at 72 and 73.

In order to prevent the auxiliary tub and cover assembly from dropping back into the main tub when lifted or partially opened, a latch mechanism is preferably provided, which is best shown in Figure 7. As there shown the rods 66 are provided at their lower extremities with cupped depressions 74 in which the detent plungers 75 are adapted to engage to hold the assembly in raised position. The plungers are urged outwardly, and their tapered ends urged into the depressions 74, when the assembly is lifted so that the rods are in the proper position, by engagement of oppositely inclined cam surfaces 77 of the plunger 78 with the complementary inclined rear faces 79 of the detent pins. The plunger 78 is normally urged upwardly by the spring 76. The taper of the sides of the depressions 74 in the rods 76 substantially corresponds to the inclination of the tapered ends of the detent pins, and the arrangement is such that when the plunger is moved downwardly by pressing upon the finger piece 80, the weight of the combined cover and tub assembly is sufficient to force the pins 75 inwardly under the cam action of the side walls of the cups 74 upon the chamfered ends 75' of the pins, since the wedging action of the plunger 78 is then released and the pins are free to move inwardly into the spaces 81. In order to move the assembly 63 downwardly into the fully closed position shown in Figures 1, 2 and 10 it is thus merely necessary, after it has been swung to the position shown in Figure 5, to depress the finger piece 80, whereupon the weight of the slideable assembly forces the pins inwardly in the direction indicated by the arrows 82 of Figure 7 and it then drops until lower edge 63' of the member

63 contacts the bottom of the tub, as shown in Figure 10.

When the machine is in use for any purpose in which water is contained within the main tub, the edge 63' is below the water level, and an effective water seal is thus established which positively prevents any possibility of leakage or splashing. On the other hand, when the assembly supporting and including the member 63 is thrown back to the position shown in Figure 6, the member 63 provides an auxiliary tub of substantial capacity, in fact its capacity exceeds that of the main tub. A bumper of rubber or the like, as 83, is preferably secured to the leg 17 to prevent the side rails 65 of the auxiliary tub and lid-supporting framework from striking the leg 17 when this assembly is in opened position, as will be clearly understood from an examination of Figure 6. Since the supporting framework 64-65 and the leg 17 are of strong and rigid construction, the support for the member 63 when used as a tub is adequate, even though large quantities of water, wet clothes, or other heavy objects be placed therein.

Any suitable means may be utilized for draining the tub when it is desired to empty the same. The draining means here shown comprises a sump 84 secured in an aperture in the bottom of the tub, or in a depressed well 15' so arranged that the entire contents of the tub may readily drain into the sump, which constitutes its lowest point. A removable perforated catch plate, as 85, may be provided if desired, being shown furnished with a handle 86 to permit its easy removal. A drain and clean-out plug 87 is shown threaded into the bottom of the sump and the outlet connection thereto, to which the draining hose may be attached by simply slipping its end thereover, comprises a simple pipe 88 extending from the side of the sump, but so arranged within the sump that its only opening is at the very bottom of the reduced portion of the trap, thus insuring against the draining means drawing air until the tub has been completely emptied. As shown in Figure 2 the draining hose may comprise two sections, 89-90, the former extending from the nipple 88 to the short coupling pipe section 91 supported from the leg 18 by the bracket 92, while the latter extends from the upper extremity of the coupling pipe 91 to an ejector device 93 secured to one of the sink water faucets 94.

The ejector 93 may be of any of the well known constructions, usually operating upon the Venturi principle, and creating a partial vacuum in the side pipe 95 to which the hose 90 is connected when the water, which flows straight through the device and into the sink, is turned on. Its construction need not here be considered in detail, for it is believed that the manner of applying this well known device to draining the tub will be clearly understood. When it is desired to drain the auxiliary tub 73 or the clothes-washing tub 96, it is merely necessary to remove the hose 90 from the coupling 91, to which it is secured merely by friction, and drop the end of the hose into the tub desired to be emptied. Of course water may be emptied from either of the tubs 63-96 by simply pouring such water into the main tub and then draining it from the sump. When it is desired to fill the main tub 15, it is merely necessary to close the end of the ejector unit 83, as with the finger, whereupon the water will be forced through the hoses 89-90 and into the tub through the sump. The tubs 75

63—96 may be filled in the same fashion by means of the hose 90, which may be removed from the coupling 91 for such purpose. For cleaning, the entire machine may be tilted, with the lid open, to the position shown in Figure 12. It may then be conveniently scrubbed or brushed out.

The main drive shaft 62 of the machine extends from the transmission housing 22 upwardly through the bottom of the tub. The transmission housing is formed with an integral threaded boss or nipple 97 which extends upwardly through the bottom of the tub surrounding the shaft, and the joint is sealed by means 15 of nuts 98 and suitable packing gaskets as 99. By means of a suitable transmission, (the details of construction of a preferred form of which are described in my copending application Serial Number 594,681, filed February 23, 20 1932) the shaft 62 may be rotated at either low or high speed, or may be oscillated, as desired. The details of construction of the transmission, and its mounting with respect to the machine itself, are of course more or less optional, and need not be considered herein. In the construction shown, the various shaft movements are obtained and the transmission is controllable by means of a shifting lever 100 fulcrumed in the housing 23 and connected to the 25 transmission by means of the shaft 101. The upper extremity of the shaft 62 is splined, as 30 at 102.

When it is desired to utilize the machine for washing dishes, pans, vegetables or the like an impeller, as 103, is secured to the shaft 62, the impeller being of course cooperatively socketed to fit over the shaft and engage the splines. The impeller is contoured to throw water upwardly and outwardly in all directions within 35 the tub, and due to the natural downward thrust upon it when in use, no additional securing means is required to hold it upon the shaft 62. A removable rack as 104 for dishes and other objects desired to be washed, may be 40 placed within the tub when the machine is desired to be used for this purpose. The details of construction of a suitable rack are disclosed in my copending application Serial Number 530,119, filed on the fourteenth day of April, 45 50 1931, although any other rack construction might of course be employed. Its details need not herein be again considered. For the dish washing operation the transmission is ordinarily adjusted to drive the impeller at the high speed. 55 The lid is of course closed.

When it is desired to wash clothes in the machine, the impeller 103 and dish-rack are removed, and the tub 96 placed upon the shaft 62, for driving thereby. The tub 96 is provided 60 with an upper portion 105 constituting an inwardly extending overhanging edge adapted to prevent splashing of water from the clothes-washing into the dish-washing tub. An impeller or agitator 106 is rigidly secured to and 65 within the clothes-washing tub, and seals the bottom thereof, as shown in Figure 10. It also is socketed to fit over the shaft 62 and cooperatively engage the splines 102. It is believed that the operation of the clothes-washer 70 will be readily apparent. It is of the agitator type, and when the transmission is set to oscillate the entire assembly, the swirling action set up by the vanes of the agitator 106 forces water or suds placed in the tub 96 75 through the fabric being washed.

Any other accessory devices which may be desired to be directly secured to the drive shaft 62, such as a grinder, buffer, pot scourer, drill or the like, may be attached by means of a simple chuck arrangement, such as is shown 5 in my copending application, Serial Number 530,120, filed on the fourteenth day of April, 1931.

Other accessory apparatus requiring additional support may be secured to the machine by 10 means of the removable cross bar 107, which is terminally provided with thumb screws 108, whose ends project downwardly therefrom for cooperative engagement in threaded apertures 109 tapped in the tops of the legs 16, 19, as 15 shown in Figures 1 and 12. The contour of the cross bar is shown in Figures 6 and 12. It is centrally provided with a downwardly extending elongated boss as 110, which may be braced by webs 111, bored and provided with suitable bearings for journaling the extension shaft 112 which at its lower extremity carries the interiorly splined cup 113 adapted to align with and couple the extension shaft to the main drive shaft 62 when the cross bar is in position. The 20 extension shaft may be divided into two sections (112—112') by a flexible coupling as 114, the upper extremity of the shaft terminates within the upwardly opening socket 115 formed in the cross bar, and secured to the shaft within 25 the socket may be the coupling collar 116, across the upwardly opening cupped portion of which auxiliary devices may be driven. Devices 30 designed to be supported by the cross bar and be 35 driven by the extension shaft are provided with supporting plug portions adapted to slidably fit within the socket 115, through which plug portions a drive shaft extends. The plug portion 120 shown carried by the beater assembly illustrated in Figure 12 serves to illustrate this construction. To secure such attachments against 40 rotation I preferably form upon the cross bar at a point spaced from the socket an upwardly extending boss or locating pin 121 over which 45 suitable apertures correspondingly formed in the various attachments are adapted to fit. Suitable securing means adapted to prevent undesired displacement of such attachments may be incorporated with the locating boss 121. As 50 shown in Figure 12, the boss, which extends downwardly as well as upwardly from the cross bar, may be slotted as at 122, and the latch member 123 pivoted in the slot upon the horizontal pivot pin 124. The latch piece is adapted 55 to project upwardly from the boss and overhang a cooperating portion of the attachment to prevent its removal. As shown in Figure 12, the bottom portion 125 of the supporting housing of the whipper attachment may be formed 60 with a laterally extending apertured lug 126 adapted to fit over the pin 121, while when in this position the latch piece 123 overhangs the top of the lug to prevent removal of the attachment. The top of the latch hook is inclined, as 65 clearly shown in the drawings, so that the attachment may be secured by merely aligning the lug with the boss and forcing it downwardly thereover, during which movement the latch piece will be forced inwardly and then snap out 70 into the latching position in which it overhangs the edge of the aperture in the lug, under the influence of the spring 127.

Within the housing 125 may be arranged step-up gearing, the details of which are not neces- 75

sary here to be shown, and the shaft of the final gear of the step-up train extends upwardly through the boss 128 carried by the cover plate 129 of the housing 125. A suitably formed container or receptacle 130 is formed to fit over the boss 128, where it is frictionally positioned in the manner clearly shown in Figure 12. To the other extremity of the drive shaft 131 which projects from the top of the boss 128 may be coupled any suitable device or devices, as for whipping or otherwise treating the contents of the receptacle, or for shredding or extracting material which then falls into the receptacle. A whipping or beating attachment is shown secured to the shaft 131. The whippers themselves are designated 132, and are supported from a housing 133 which serves also as a lid for the container and as a housing for the gears 134—135 through which the whippers are driven. A handle, as 136, is secured to the housing and the attachment may be removed by merely lifting. Since the receptacle 130 is free to turn upon the boss 128, it may do so during a whipping operation, and in fact, because of this floating arrangement of the container, the frictional engagement between the material being whipped and the side walls is sufficient to slowly turn the receptacle while the whipper is in operation, to thus insure thorough beating of the entire contents.

In Figures 13, 14 and 15 I have shown a hair-drying attachment adapted to be mounted upon the cross bar in a manner similar to that in which the whipper just described is shown mounted thereon in Figure 12. As shown in Figures 14 and 15, the lower supporting portion of the device comprises a gear housing 225 and a downwardly extending boss or plug portion 220 adapted to fit in the socket 115 of the cross bar, and in which is journaled a shaft 237 adapted to be driven by the extension shaft 112 through the pin 117 in the manner previously described. The apertured lug 226, formed to cooperatively engage the upstanding boss 121 and latch piece 123 may be of similar construction to the analogous structure shown and described in connection with the whipping attachment. The upper portion of the hair-drying attachment comprises a centrifugal blower, the case of which is designated 238 and the impeller 239. The latter is driven from the shaft 237 through step-up gearing comprising the gear 240 and pinion 241. The latter is fast upon the impeller shaft 242. In the blower intake, 55 which is shown positioned in the side of the casing in the conventional manner, is arranged an electrical heating element 243 adapted to warm the air entering the blower, all of which must pass through the perforated heater casing 244 secured, as by screws 245, over the blower inlet 246. The required current supply for the heater may be conducted thereto by the flexible cord 247, which may be fitted with a plug (not shown) adapted to be inserted in the socket 26 60 previously described, and shown in Figure 1. The nozzle 248 of the hair-dryer may be secured to the blower outlet 249 by a ball and socket joint 250 to render it capable of limited universal movement. It is believed that the operation of the hair drying attachment will also be readily apparent. It will be seen that when the device is installed upon the cross bar, and the cord 247 electrically connected to the outlet receptacle 26, turning on the current by means of the switch 25 both starts the blower

and turns on the current to the heater 243, while throwing the switch to the off position stops the blower and shuts off the heater current.

As shown in Figures 6 and 13, the cross bar 107 carries a laterally projecting extension 137 which is terminally apertured as at 138. This apertured extension constitutes additional locating means adapted to assist in firmly positioning upon the cross bar one or more other accessory attachments not herein described, such as the ironer shown and described in my copending application Serial Number 530,118, filed on the fourteenth day of April, 1931, the method of attachment of which is also clearly shown in such copending application.

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

What I claim is:

1. In a machine of the character described, a main tub, an auxiliary tub forming a closure member for the main tub, securing means including a horizontal pivot portion hingedly connecting said member to the main tub, said member and the main tub being of different diameters 30 to permit them to nest one within another, means slidably connecting said member and said securing means, whereby said member may either be swung to a position open end uppermost beside the main tub to serve as an auxiliary tub of substantial capacity, or may be nested with the main tub to serve as a closure member therefor.

2. In a machine for washing and the like, a main tub, a combined closure and auxiliary tub 40 member therefor of slightly lesser diameter, a swingable frame, a horizontal pivot portion for hingedly connecting the same with the main tub member, means slidably connecting the auxiliary tub and said frame member, whereby 45 said auxiliary tub may be swung to an open end down position over the main tub, and may be moved downwardly within the main tub until its rim lies adjacent the bottom of said tub, or may be moved upwardly and then swung to an 50 inverted upwardly opening position beside the main tub.

3. In a washing machine, a main tub, a support extending up the side of the main tub to a point adjacent its rim, an auxiliary tub of 55 lesser diameter than the main tub forming a closure member therefor and adapted to slidably fit within the main tub, and means swingably and slidably securing the closure member to said support including a member pivoted to 60 said support for swinging movement about a horizontal axis, and means slidably connecting the closure member to said pivoted member, whereby the closure member may be swung either to a position open end down over and 65 in substantial alignment with the main tub and lowered into the same, or moved to an inverted upwardly opening position therebeside to serve as an auxiliary tub.

4. In a washing machine, a main tub, a cupped 70 closure therefor having a mouth and a body portion of lesser diameter than the main tub, the height of which closure member is at least substantially as great as the inside height of the main tub, the closure member being propor- 75

- tioned to interfit with and vertically slidable in the tub, means within the main tub for projecting water therewith against the interior of the closure member when fitted mouth down 5 into said main tub in inverted position, handle means on the closure member for moving said member in and out of the tub, whereby said closure member, when so arranged in inverted position in the main tub with its mouth abutting the bottom of said main tub may extend beneath the level of water in such tub to form a seal, and whereby said closure member may also be removed from the main tub and used mouth up 10 as a separate tub of substantial capacity with relation to the main tub.
5. In a washing machine, a main tub, a closure member therefor comprising a cupped member, means supporting the cupped member adjacent the main tub, including horizontal pivot portions 20 and vertically slidable portions to which said member is attached, whereby it may be moved to a raised position above and in substantial alignment with the main tub, and slid downwardly into nested relation therewith, and latching means cooperating with said slidable portions for holding the closure member in raised position and releasable at will to permit its downward movement.
6. In a washing machine, a main tub, supporting means therefor, an auxiliary tub and closure member for the main tub proportioned to telescopically interfit with said tub when slid vertically relatively thereto, means for supporting said member open end uppermost adjacent the main tub, and latch means for holding said closure member in raised inverted position over the main tub and releasable at will to permit downward movement of the closure member into interfitted relationship to the tub.
7. In a device of the character described, in combination with a main tub, a supporting portion extending vertically of and outside a wall of said tub, a hinging element pivoted to said supporting portion adjacent the top thereof, a closure and auxiliary tub member slidable within the main tub, a portion carried by said member slidably connected to said hinging element, and latching means for releasably holding said member against sliding into the main tub.
8. In a device of the character described, in combination with a main tub, a supporting portion arranged substantially at the top of said tub, a hinging element pivoted to said supporting portion, a closure and auxiliary tub mem-

ber slidable within the main tub, a portion carried by said member and also slidable within the tub and slidably connected to said hinging element, and latching means operable from outside the main tub for releasably holding said member against sliding into the main tub. 5

9. In a device of the character described, in combination with a main tub, a bracket portion mounted outside and arranged near the top of said tub, a hinging element pivotally carried 10 by said bracket portion and swingable about an axis transverse to the tub, a closure and auxiliary tub member carried by and swingable with said hinging element proportioned to fit within the main tub, a supporting portion for said member 15 and providing sliding connection between the same and the hinging element and slidable with said member within said tub in a path generally parallel to the axis of and at least equal to the internal height of the main tub, said hinging 20 element being swingable throughout substantially 180°, whereby said member while remaining attached thereto may be slid downward into the main tub or elevated to a position clear thereof and swung to an inverted position there- 25 beside.

10. In a device of the character described, in combination with a main tub, a bracket portion mounted near the top of said tub, a hinging element pivotally carried by said bracket portion 30 and swingable about an axis transverse to the tub, a closure and auxiliary tub member carried by and swingable with said hinging element proportioned to fit within the main tub, a supporting portion carried by said member and providing 35 sliding connection between the same and the hinging element and slidable with said member within said tub in a path generally parallel to the axis of and at least equal to the internal height of the main tub, said hinging element 40 being swingable throughout substantially 180° whereby said member while remaining attached thereto may be slid into the main tub or elevated to a position clear thereof and swung to an inverted position therebeside, and latching 45 means including a control member carried by said hinging element for preventing said closure and auxiliary tub member from sliding into the tub.

11. Apparatus as set forth in claim 10 including projecting means for automatically engaging the latching means when said auxiliary tub and closure member are pulled out of the tub. 50

GEORGE K. PARSONS.
